ENGINE VALVE.

1,417,590.

Specification of Letters Patent. Patented May 30, 1922.

Application filed July 3, 1920. Serial No. 393,881.

To all whom it may concern:

Be it known that we, JOHN R. WARREN and ALFRED BRECHTING, citizens of the United States, residing at Grand Rapids, in the county of Kent and State of Michigan, have invented new and useful Improvements in Engine Valves, of which the following is a specification.

The present invention relates to engine valves; and an object thereof is, generally, to provide a rotary valve for controlling the operation of an engine, which although sufficiently tight to prevent leakage shall not be subject to binding and sticking occasioned by heating or otherwise; and more particularly, to provide a bushing surrounding such a valve; and further, to provide such a bushing which shall readily and sufficiently yield to expansive and contractive forces. The employment of rotary valves for controlling the operation of engines, particularly internal-combustion engines, has been found objectionable on account of their tendency to expand under the influence of heat or other causes, and for this or other reasons to bind or stick in their bearings or chambers. The principal object of this invention is to avoid this difficulty.

The above and any other objects herein-after appearing are attained by, and the invention finds preferable embodiment in, the structure hereinafter particularly described and illustrated by the accompanying drawings, in which:—

Figure 1 is a side view of an internal-combustion engine to which my valve is applied, certain parts being broken away;

Figure 2 is a transverse vertical sectional view thereof taken on a plane corresponding to line 2—2 of Figure 1;

Figure 3 is a transverse horizontal sectional view of three of the engine cylinders taken on a plane corresponding to line 3—3 of Figure 1;

Figure 4 is a view in perspective of a bushing or sleeve surrounding the valve; and

Figure 5 is a view in perspective of a block carrying three of the engine's cylinders and a portion of the valve's casing.

Our invention, at least in its broader aspects, is applicable to engines of various kinds, but in the embodiment thereof chosen for illustration by the drawings and for de-

tailed description in the body of this specification, our invention is shown in connection with a four-cycle type internal-combustion engine having six cylinders, 1, 2 and 3 thereof appearing in diametrical longitudinal section in Figure 1, the invention being particularly well adapted for use in internal-combustion engines. The cylinders have pistons 4, 5, 6, furnished with connecting rods 7, 8, 9, for operating the cranks 10, 11, 12 respectively, on the crank shaft or engine shaft. At their upper ends the cylinders have ports 61, 62, 63 respectively for the admission of the operating fluid thereinto and for the expulsion of the products of combustion therefrom. These cylinders are supported (as hereinafter described) on the frame, designated generally 14, of the engine and are slightly movable relatively thereto in their longitudinal direction. The rotary valve 15 for controlling the admission of the operating fluid to the cylinders and for permitting the expulsion of the products of combustion therefrom, rotates in a bearing or valve chamber in a valve casing, designated generally 16, having ports communicating with the cylinders through the cylinders' said ports respectively. This valve casing 16 comprises two portions, being longitudinally split to form the same, the upper 18 of which portions is supported in connection with and, as shown, forms a part of the frame 14, and the lower portion 19 of which casing, adjacent the cylinders' ports, is supported in connection with and, as shown, forms a part of the cylinders. The cylinders are mounted, that they may have a slight and cushioned movement relatively to the frame as above stated, by their lugs 20 bolted at 21 to stiff resilient strips 17 supported intermediately said lugs by the lugs 22 on the engine frame bolted at 23 to the strips 17. By reason of this mounting, the two portions 18, 19, of the valve casing are pressed toward each other, and the valve casing's lower portion 19 (or tantamount thereto, the casing's bushing 34) is yieldingly held in contact with the valve 15 itself. As shown, means are provided to prevent leakage between the two portions of the valve casing; such means may manifestly be of various forms, but in the construction illustrated, such means consists in said bushing or sleeve 34 contained in the

valve casing and surrounding the rotary valve and having openings 35 which register with the cylinders' ports respectively. To provide for the expanding and contracting 5 of this bushing, various means may be adopted, as by providing the bushing with a series of slits 36 extending in the axial direction of this bushing and disposed end to end, and another similarly arranged series 10 of like slits 37, the slits of one series being in staggered relation to those of the other series, said slits not registering with the joint between the casing's two portions. It will be seen that, although the rotary valve 15 15 (and the bushing with it) may expand through heating, it will not bind or stick in its chamber, inasmuch as the resilient strips 17 will permit the cylinders and the lower portion 19 of the valve casing to slightly 20 move relatively to the frame and the casing's upper portion 18 and thus expand the valve chamber in a vertical direction sufficiently to prevent such binding or sticking, at the same time retaining the valve sufficiently tight in its chamber, particularly in 25 the region of the cylinders' ports, to prevent leakage. And further and more particularly; inasmuch as valve leakage is principally occasioned by pressure in the cylinder due 30 to the expansive fluid therein (in the case of steam engines and the like) or by the firing of the explosive fluid therein (in the case of internal-combustion engines), or— and in less degree—by the "compression 35 stroke" of internal-combustion engines, it will be seen that this very pressure is the force which tightens the valve at the very time it tends to leak, and that when such pressure expends itself such tightening of 40 the valve ceases. The valve is hollow, having longitudinally extending passages 24, 25 to which the fluid is supplied from a vent 26 in the block 27 carrying the cylinders, the fluid thence passing through a series of inlets 51 through the valve's wall, and to each cylinder's port through diametrically opposite openings 28, 29 in the valve's wall, the products of combustion being discharged from each cylinder through diametrically 45 opposite outlets 30, 31 through the valve's wall and into its longitudinally extending passages 32, 33 opening at the ends of the valve into exhaust pipes 53. These inlets, 50 openings and outlets through the valve's wall 55 are so disposed angularly of the valve that the sequence of supply to and exhaust from the several cylinders is properly timed.

As shown in Figure 1, the engine's crank shaft carries a skew gear 38 meshing with 60 a skew gear 39 on the vertical shaft 40, between the third and fourth cylinders and rotatable in bearings 41 on the frame, said shaft having a skew gear 42 meshing with a skew gear 43 driving the rotary valve 15, 65 whereby the valve is rotated by the crank

shaft; the gear ratios of the skew gears being such as to properly time the valve's rotation to the crank shaft's rotation. It will be seen that this arrangement and disposition of the means for rotating the valve 70 is peculiarly compact and positive and effective in operation. A water jacket surrounds the cylinders, the water containing space being designated 44, 45, water being supplied by the pipe 46 and discharged by 75 the pipe 47. To permit the free circulation of the water between the upper portion 44 of the water jacket and its lower portion 45, short tubes 48 are carried by either the cylinder block 27 or the frame 14 and slidably 80 bear in the other. A compressible packing 49 is inserted at the free ends of these tubes. Openings for the cylinders' spark plugs are indicated at 50 and a lubricating wick is shown at 56. 85

It will be seen that the views show an example of a bushing surrounding the valve and having slits extending in such a direction as to augment the lateral expansibility and contractability of the bushing and yet so 90 located that communication therethrough between the valve's exhaust and intake passages is prevented. We desire to claim this feature broadly.

The invention being intended to be pointed 95 out in the claims, is not to be limited to or by details of construction of the particular embodiment thereof illustrated by the drawings or hereinbefore described.

We claim:

1. In an engine; a frame; a cylinder longitudinally movable relatively thereto; a rotary-valve casing comprising a portion supported in connection with the frame and another portion supported in connection with the cylinder and having a port communicating with the cylinder; a bushing, between the valve and valve casing, extending over the adjacent parts of said portions of the valve casing and having an opening registering with said port and having a series of axially-extending slits disposed end to end and a second series of axially-extending slits disposed end to end, the slits of one series being staggered relatively to those of the other series; a valve rotatable in said casing and adapted to open and close said port. 100

2. In an engine; a frame; a cylinder longitudinally movable relatively thereto; a 110 rotary-valve casing comprising a portion supported in connection with the frame and another portion supported in connection with the cylinder and having a port communicating with the cylinder; a bushing, between the valve and valve casing, extending over the adjacent parts of said portions of the valve casing and having an opening registering with said port and having a 115 series of axially-extending slits disposed end 120

125

130

to end and a second series of axially-extending slits disposed end to end, the slits of one series being staggered relatively to those of the other series and extending beyond the 5 ends of the slits in said other series; a valve rotatable in said casing and adapted to open and close said port.

3. In an engine; a rotary - valve casing having ports communicating with the engine's cylinder; a valve rotatable in the casing and having intake and exhaust passages communicating with said ports in certain positions of the valve; a bushing between the

valve and valve casing having openings registering with said ports and slits extending 15 in such direction as to augment the lateral expansibility and contractability of the bushing and so located as to prevent communication therethrough between the valve's said passages.

In testimony whereof we have hereunto set our hands at Grand Rapids, Michigan, this 25th day of June, 1920.

JOHN R. WARREN.
ALFRED BRECHTING.
